FIREPROOF CONTAINER

Manuel Essman, New York, N. Y.

Application April 24, 1948, Serial No. 23,112

10 Claims. (Cl. 206—52)

1

The present invention relates to improvements in fireproof containers for film rolls and other inflammable material.

Motion picture film rolls are generally stored in specially constructed fireproof vaults which are of expensive design and which obviously afford protection to the film rolls only while they are actually in storage. Since films are constantly being shipped from some central distribution point to exhibitors, often traveling over great distances and being subjected to varying conditions and hazards, it is desirable to provide a container for individual film reels which will afford maximum protection against fire hazard and mechanical injury in transit.

Accordingly it is the primary object of the invention to provide a fireproof container of simple design and construction having a central inner compartment for housing an individual film reel and an outer compartment containing fire retarding material for the protection of the film reel.

Another object of the invention is the provision of a fireproof container of the character indicated which will maintain the film reel in tightly coiled condition preventing buckling and minimizing the possibility of mechanical injury and damage to the edges of the film in transit.

A further object of the invention is the provision of a fireproof film container having improved integral handle means for transporting the container.

Another object of the invention is the provision of a fireproof container which may be fabricated inexpensively, which is of highly compact construction and which is so designed as to stand upright on a supporting surface, such as a table, floor or shelf.

The foregoing objects as well as additional objects and advantages of the invention will be readily apparent in the course of the following detailed description taken in connection with the accompanying drawing which illustrates a preferred embodiment, and wherein:

Fig. 1 is a plan view of the base portion of the container.

Fig. 2 is a plan view of the cover portion of the container.

Fig. 3 is a cross sectional view taken along line 3—3 of Fig. 2.

Fig. 4 is a cross sectional view taken along line 4—4 of Fig. 1.

Fig. 5 is a plan view of the assembled container.

Fig. 6 is a side elevation of the assembled container.

2

Referring now to the drawings in greater detail, the container may be constructed from sheet metal and comprises the complementary, interfitting base portion 10 and cover portion 11.

5 Said base portion and cover portion are preferably formed with flat bottom walls 10a and 11a respectively, flat side walls 10b and 11b respectively and interconnecting flat walls 10c and 11c respectively, the remaining portion of the peripheral walls being substantially circular, as shown in the drawing. An integral handle grip portion 12 is also formed on the base portion and cover portion.

15 Wall portions 10a, 10c and 10b and the respective intervening circular wall portion define the outer peripheral flange 13 of base portion 10 while wall portions 11a, 11c and 11b and the respective intervening circular wall portion define the outer peripheral flange 14 of interfitting cover portion 11.

20 Base portion 10 is further provided with a circular inner partition 15 defining a central circular inner compartment 16 and an outer compartment 17. Similarly, cover portion 11 is provided with a circular inner partition 15a defining a central circular inner compartment 16a and an outer compartment 17a. Within each of the outer compartments 17 and 17a there is placed a layer or blanket 18 of suitable fire-retarding material, such as asbestos or the like.

25 In the preferred embodiment of the invention maximum fireproofing protection is afforded to the film reel by providing for interfitting, telescopic engagement between the circular partition 15 and the circular partition 15a upon engagement of base portion 10 and cover portion 11. In addition circular partition 15 may be provided with spaced vertical grooves 19 for the reception of correspondingly spaced ribs 20 in order to more effectively retain, protect and seal the film reel disposed within the central compartment of the container.

30 In order to facilitate removal of the film reel, circular base portion 15 is preferably provided with a pair of diametrically opposed cutouts or recesses 21 which receive cooperating lugs 22 formed on circular cover partition 15a in the closed condition of the container.

35 In order to securely interengage base portion 10 and cover portion 11 during shipment the outer surfaces and peripheral walls thereof may be provided with pairs of spaced ribs or protuberances 23 defining diagonally extending guide channels 24 for the reception of fire-retarding strap elements 25 of asbestos or other

suitable material which may be fastened in place by means of conventional buckles 26 or the like.

The invention is not to be limited to the specific shape of container shown although the provision of a flat bottom edge and flat side edge enable the containers to be maintained in upright position and to be compactly and conveniently arranged on a shelf. The cover portion or closure member may have an overfitting flange which coacts with the flange of the body portion, rather than having a recessed flange as shown in the drawing. Further, the telescopic engagement of the circular inner partitions of the body and cover members together with the interengaging grooves and ribs may be omitted, if desired, while still retaining effective fireproofing characteristics for the container.

The container may be used effectively for transporting both raw, light sensitive film and finished film rolls. The design of the container combines maximum fireproofing protection which enhances facility of handling and storage. The outer peripheral walls of the container act as buffers to take the full load of denting and rough handling which normally adversely affect the edges of the outer convolutions of coiled film in conventional film cans, subsequently causing film to feed improperly or even tear in the projector, and therefore the container affords considerably greater protection against wear and abuse during transportation than has heretofore been possible.

Since certain additional modifications may be made in the fireproof container of the present invention without departing from the scope thereof, it is intended that all matter contained in the foregoing specification and shown in the accompanying drawing be interpreted merely as illustrative and not in a limiting sense.

What is claimed is:

1. A fireproof container for film rolls comprising complementary, interfitting body and cover portions, said body and cover portions each having an inner partition defining a central inner compartment and an outer compartment and fire-retarding material disposed in said outer compartment.

2. A fireproof container for film rolls comprising complementary, interfitting body and cover portions, said body and cover portions each having a circular inner partition defining a central inner compartment and an outer compartment and fire-retarding material disposed in said outer compartment.

3. A fireproof container for film rolls comprising complementary, interfitting body and cover portions, said body and cover portions each having a circular inner partition defining a central inner compartment and an outer compartment, fire-retarding material disposed in said outer compartment, and integral cooperating handle elements formed on said body and cover portions.

4. A fireproof container for film rolls comprising complementary, interfitting body and cover portions, said body and cover portions each having a circular inner partition defining a central inner compartment and an outer compartment, fire-retarding material disposed in said outer compartments, integral cooperating handle elements formed on said body and cover portions, cooperating guide channels formed in the outer

surfaces of said body and cover portions and fire-retarding strap elements disposable within said guide channels for securely interengaging said body and cover portions.

5. A fireproof container for film rolls comprising complementary, interfitting body and cover portions, said body and cover portions each having a circular inner partition defining a central inner compartment and an outer compartment, fire-retarding material disposed in said outer compartments, said body and cover portions each including a flat bottom wall, a flat side wall and a flat intervening wall, the remaining outer peripheral wall being substantially circular and integral cooperating handle elements formed on said body portion.

6. A fireproof container for film rolls comprising complementary, interfitting body and cover portions, said body and cover portions each having a circular inner partition defining a central inner compartment and an outer compartment, fire-retarding material disposed in said outer compartments, said body and cover portions each including a flat bottom wall, a flat side wall and a flat intervening wall, the remaining outer peripheral wall being substantially circular and integral cooperating handle elements formed on said body portion, cooperating guide channels formed in the outer surfaces of said body and cover portions and fire-retarding strap elements disposable within said guide channels for securely interengaging said body and cover portions.

7. A fireproof container in accordance with claim 3 wherein said circular inner partitions are arranged for telescopic interengagement, one of said partitions having spaced vertical grooves formed therein, the other of said partitions having cooperating ribs engageable within said grooves, whereby to protect and seal a film roll within the central inner compartment of the container.

8. A fireproof container in accordance with claim 4 wherein said circular inner partitions are arranged for telescopic interengagement, one of said partitions having spaced vertical grooves formed therein, the other of said partitions having cooperating ribs engageable within said grooves, whereby to protect and seal a film roll within the central inner compartment of the container.

9. A fireproof container in accordance with claim 5 wherein said circular inner partitions are arranged for telescopic interengagement, one of said partitions having spaced vertical grooves formed therein, the other of said partitions having cooperating ribs engageable within said grooves, whereby to protect and seal a film roll within the central inner compartment of the container.

10. A fireproof container in accordance with claim 6 wherein said circular inner partitions are arranged for telescopic interengagement, one of said partitions having spaced vertical grooves formed therein, the other of said partitions having cooperating ribs engageable within said grooves, whereby to protect and seal a film roll within the central inner compartment of the container.
